R. SERGESON AND COMPANY, OF PHILADELPHIA, PENNSYLVANIA

SHUTTLE

Application filed June 25, 1931. Serial No. 546,862.

This invention relates to improvements in shuttles and more particularly to improvements in means for tensioning the yarn in the shuttles.

5 The principal object of the invention is to provide a tensioning device of novel and improved character and of great simplicity of form.

Another object of the invention is to provide a device of the stated character which may be readily and accurately adjusted to regulate the tension of the yarn.

Another object of the invention is to provide a novel tensioning means which is capable of removing lint and flies from the yarn passing through the shuttle.

The invention further resides in certain features and details of construction set forth hereinafter and shown in the accompanying drawing, in which:

Figure 1 is a plan view of one end of a shuttle showing sufficient of the parts to afford an understanding of the present invention;

25 Fig. 2 is a front elevation view of Fig. 1;
Fig. 3 is a transverse view in section on line 3—3, Fig. 1;

Fig. 4 is a longitudinal view in section on line 4—4, Fig. 1;

30 Fig. 5 is a view in perspective showing the tension member completely removed from the shuttle; and

Fig. 6 is a view in perspective from a different angle of the disclosure of Fig. 5.

35 Referring to the drawing the numeral 1 represents the body of a shuttle which may be of standard form. Towards one end and in the interior thereof the shuttle comprises a yarn tensioning device which, in a preferred form comprises a guide member 2 provided with a longitudinally extending threading groove 3 having an overhanging guard 4 extending thereover at least in part. The groove 3 in the present instance communicates with an underlying longitudinally disposed bore 5 in which the yarn normally travels through the tension member. The guide body is further provided with a transversely disposed thread groove 6 extending outwardly of and connecting with the longitudinally

disposed yarn bore 5. Furthermore to effectively guide the thread through the tensioning device, that portion of the guide body overhanging the transverse yarn groove 6 is formed in a depending hook element 7 intermediate which, and the groove 6, the yarn is arranged to pass. The guide 2 is provided with a transversely disposed bore 8 suitably arranged therein for facilitating the securing thereof in the shuttle body 1, as shown in Figs. 1 and 2, by means of a threaded screw element 9.

55 To effectively and readily tension the yarn passing through the member 2, we provide a resilient wire element 10 in the novel form shown in Figs. 5 and 6 of the drawing. The tension element 10 is provided in the preferred form with a loop 11 which embraces a depending lug 12 on the lower face of the guide body 2, for securing the said element 10 thereto. The said element 10 further comprises integral arms 13, 13a extending rearwardly from the loop 11 and passing in parallel adjacent relation along the rear face of the guide body 2. At the upper portions thereof the said arms 13, 13a are curved outwardly with respect to the parallel upstanding portions thereof and downwardly to form loops lying flat against the rear face and subsequently pass about the vertical rear edges of the body and along the side faces thereof, the terminal portions engaging the bottom edges at each side of the lug 12. The tension in the yarn is effected by arranging the yarn to pass intermediate the upstanding adjacent portions 13, 13a of the tensioning element 10. The yarn in practice also extends through the longitudinal bore 5 and intermediate the depending hook 7 and the yarn groove 6.

90 By means of the device described above, the tension placed upon the yarn as it passes between the cooperating relatively adjustable and opposed portions 13, 13a of the tension element 10, may be adjusted as desired by manually moving the said opposed portions relatively closer or further apart with respect to each other. In providing a tension adjustment of simple and novel form as in the present case, we not only are able to ef- 100

fectively regulate the tension desired in the yarn, but the relatively opposed portions 13 and 13a of the adjusting element 10 cooperate as gatherers in removing lint and flies 5 from the yarn as it passes the tension members.

Foreign substances such as described above, are further removed from the yarn by means of an obliquely disposed felt strip 10 14, removably positioned in the slot 15 in the guide body 2, and extending a sufficient distance inwardly of the longitudinal bore 5.

It is apparent that the invention is capable of other embodiments than that illustrated and it will be understood that no limitations are imposed other than set forth in the appended claims.

We claim:

1. In a shuttle for yarn a tensioning device comprising a guide body having a longitudinal yarn bore extending therethrough and a transversely disposed yarn groove connecting with and extending outwardly from said bore, a depending lug on said tensioning member, and a tensioning wire extending over a portion of said device and about said lug, the said wire having relatively opposed portions adjacent the rear end of the bore intermediate which the yarn is arranged to 25 pass to regulate the tension in the yarn.

2. In a shuttle for yarn, a tensioning device comprising a guide body having a longitudinal guide bore extending therethrough and a transversely disposed groove connecting with and extending outwardly from said bore, a depending lug on said guide body, and a tensioning wire extending over a portion of said device and about said lug, the said wire having relatively opposed upstanding arms adjacent the rear end of said bore intermediate which the yarn is arranged to pass and which cooperate to regulate the tension 35 therein.

3. In a tensioning device comprising a guide body having a depending lug on the bottom surface thereof, a tensioning element having a loop formed therein and embracing said lug, integral arms extending rearwardly of said loop and passing in parallel 45 relation along the rear face of the guide body, the upper portions thereof being curved outwardly with respect to the parallel upstanding portions and downwardly to form loops lying flat against the rear face of the body, and the terminal portions of said element 50 passing about the vertical rear edges of the body, along the side faces thereof, and engaging the bottom edges of said body.

4. In a shuttle for yarn, a tensioning device comprising a guide body having a yarn bore extending therethrough, a depending projection on said guide body, and a tensioning wire embracing the outer surface of said body and the projection, the said wire having 60 relatively opposed portions overlying one

face of the guide and the bore intermediate which the yarn is arranged to pass to regulate the tension therein.

5. In a shuttle for yarn, a tensioning device comprising a body having a longitudinal bore extending therethrough, a projection on said body, and tensioning means embracing the outer surface of said body and the projection, the said means including relatively opposed upstanding arms adjacent the rear end of said bore intermediate which the yarn is arranged to pass to regulate the tension therein. 70

6. In a shuttle for yarn, a tensioning device comprising a body having a longitudinal bore extending therethrough, a projection on said body, and tensioning means extending over the outer surface of said device and said projection, the said means including relatively opposed upstanding arms overlying one 75 face of the guide and one extremity of the bore intermediate which the yarn is arranged to pass to regulate the tension therein. 80
